(57) **CLAIM**

The ornamental design for an automobile wheel, as shown and described.

DESCRIPTION

FIG. 1 is a front elevational view of an automobile wheel, showing my new design;

FIG. 2 is a perspective view thereof;

FIG. 3 is a left-side view thereof;

FIG. 4 is a right-side view thereof;

FIG. 5 is a bottom, plan view thereof; and,

FIG. 6 is top, plan view thereof.

The broken line showing of the emblem in FIGS. 1 and 2 is included for the purpose of illustrating environment and forms no part of the claimed design.

1 Claim, 4 Drawing Sheets

FIG. 1

FIG. 2

FIG. 3

FIG. 4

FIG. 5

FIG. 6
